(57) **CLAIM**

The ornamental design for a nasal irrigator, as shown and described.

DESCRIPTION

FIG. 1 is a front, right, and top perspective view of a nasal irrigator, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a groove part; and,

FIG. 9 is a cross-sectional view of nasal irrigator of FIG. 1, taken along section line 9-9 as depicted in FIG. 2.

The broken lines shown in the drawings are included for the purpose of illustrating portions of the nasal irrigator that form no part of the claimed design.

Dot-dash broken lines framing portions of the claimed design that are illustrated for enlargements from no part of the claimed design.

1 Claim, 9 Drawing Sheets
